PARACHUTE

Doss William Kennedy, Matthews, Mo.

Application February 1, 1935, Serial No. 4,534

1 Claim. (Cl. 244—21)

This invention appertains to new and useful improvements in parachutes, and more particularly to a safety structure therefore.

The principal object of the invention is to provide means for use in conjunction with parachutes for expediting the opening thereof upon use in a positive and fool proof manner.

During the course of the following specification and claim other important objects and advantages of the invention will become apparent to the reader.

In the drawings:

Figure 1 represents a bottom plan view of the parachute.

Figure 2 represents a vertical sectional view through the parachute.

Figure 3 represents a fragmentary detailed sectional view through the valve.

Figure 4 represents a fragmentary detailed sectional view taken substantially on line 4—4 of Figure 1.

Referring to the drawings wherein like numerals designate like parts, it can be seen that numeral 5 denotes the bag of the chute, with numeral 6 denoting substantially the central portion of the bag. The edge portion 7 of the bag has secured to the inner side thereof the circumferentially extending flexible tube 8, the tube being secured to the bag by thread-loops 9 or some other suitable means.

On the inner side of the bag and to the portion 6 thereof is suitably secured the bladder 10 which is normally inflated with air when the chute is packed.

A flexible conduit 11 extends from the bladder 10 and connects with the circumferential tube 8, the latter tube being provided with a valve 12 of conventional design, which when operated will release the air from the tube 8, to permit retraction of the chute after use.

At a point where the flexible conduit 11 com-

municates with the bladder 10, an obliquely disposed barrel 13 is provided on the conduit and has the piston valve 14 therein normally projected to a position closing off the inside of the conduit 11 through the agency of a spring 15. This piston valve 14 is provided with a stem 16 from which extends the cord 17 through suitable eyes 18 on the bag and along some of the guy members 19 to terminate in a ring 20 in close proximity to the suspended jumper. 10

When the jumper leaves the aircraft, it is a simple matter for him to pull the cord 17 to move the valve 14 to an open position allowing air from the bladder 10 to pass through the conduit 11 and inflate the tube 8 so that the edge 15 portion of the bag will somewhat rigidify. In other words, the bag will open up very quickly and substantially eliminate the possibility of a parachute not opening when the usual "rip cord" has been pulled, after which the cord 17 is pulled 20 to open the valve 14.

While the foregoing specification sets forth the invention in specific terms, it is to be understood that numerous changes in shape, size and material may be resorted to without departing from 25 the spirit and scope of the invention as claimed hereinafter.

Having described the invention, what is claimed as new is:

In combination with a parachute, a compressed 30 fluid bladder secured to the inside of the parachute at substantially the center thereof, an annular inflatable tube of flexible material at the edge portion of the parachute and suitably secured thereto, a conduit between the bladder 35 and the annular tube, a valve in the conduit adjacent the bladder, a pull cord extending from the valve, and guide means on the parachute to which the pull cord is disposed.

40

DOSS WILLIAM KENNEDY.
